UNITED STATES PATENT OFFICE.

ERNEST MOCCKETTI, DECEASED, LATE OF NEW YORK, N. Y., BY LOUISE MOCCKETTI,
ADMINISTRATRIX, OF NEW YORK, N. Y.

COMPOUND STRUCTURE.

Application filed May 5, 1927. Serial No. 189,052.

The invention relates to improvements in structures made of a plastic or any suitable coherent mass in which are embedded or placed metallic reinforcements for tension.

5 The constructions herein disclosed as embodiments of the invention are webbed structures provided with main tensile reinforcements in the zones of greatest tension and special tension reinforcements in the webs.

10 The coherent mass is generally either plain concrete or a combination of concrete and particular metallic members or reinforcements.

15 The purpose of the new arrangements and features is to obtain structures of small bulk, light weight and great internal strength better suited and more economical in cases of long spans than ordinary reinforced concrete constructions. Various arrangements, de-
20 scribed herein, contribute independently to this result; however, the present specification emphasizes especially the use of wide and correctly spaced flat web bars in connection with a suitable main tensile reinforcement as
25 a means of decreasing the bulk and dead weight of compound structures through reduction of the web thickness.

30 The accompanying figures show only a few examples of the new structures comprising simple girders, a cantilever system and an arch rib, but these structures may be used in all cases where moments and shears have to be resisted or where axial forces (in tension or compression) are present besides moments and shears. As plain webbed structures or in combination with other structural members or systems they are susceptible of all the applications of web structures known or conceivable in bridge construction.

35 40 All girders or systems shown in the accompanying figures are provided with web reinforcements consisting of flat bars, that is to say, of bars of elongated form in cross-section, so placed as to intercept the web compression stresses through their wide faces.

45 In the accompanying drawings illustrating various structures embodying the invention:

50 Figure 1 is a view in side elevation of a simple girder supported at its ends, and Figs. 2 and 3 are cross-sectional views thereof on lines 2-2 and 3-3 respectively of Fig. 1.

55 Fig. 4 is a cross-sectional view of the bottom reinforcement on line 4-4 of Fig. 1, drawn to a larger scale than that of Fig. 2.

Fig. 5 represents a portion of the lower part of a girder provided with two sets of web bars and a main tensile reinforcement made of riveted shapes, and Figs. 6 and 7 are sectional views thereof taken on the lines 6-6 and 7-7 of Fig. 5.

60 Fig. 8 is a view in side elevation of the end part of a girder in which the main tensile reinforcement consists of riveted flat bars, and Fig. 9 is a view in cross-section thereof on the line 9-9 of Fig. 8.

65 Fig. 10 is a view in side elevation of half of a cantilever system, and Figs. 11, 12, 13 and 14 are enlarged views in cross-section taken on the lines 11-11, 12-12, 13-13, and 14-14, respectively.

70 Fig. 15 is a view in side elevation of one half of an arch rib, Fig. 16 being an enlarged sectional view thereof near the crown, on the line 16-16 of Fig. 15, and Fig. 17 being an 75 enlarged horizontal sectional view of its abutment on the line 17-17 of Fig. 15.

75 In order to clearly show the various reinforcements of the structures represented, all metallic parts, although entirely em- 80 bedded in the coherent mass, have been shown in full lines in Figs. 1, 5, 8, 10 and 15, the enveloping part of the structure being represented in broken lines.

85 An idea of the special features of the pres-
90 ent constructions may be had by referring for instance to the simple girder shown in Figs. 1, 2 and 3. The tension reinforcement for this girder may consist of a continuous main tensile reinforcement running along the bottom edge of the girder and web bars connected to the main tensile reinforcement. The coherent mass may be concrete in which may be embedded two main steel members for comp-
95 pression running along the upper edge of the girder and one steel web post above each of the supports A and B. The main tensile reinforcement may be composed of four spaced steel plates *p* placed vertically, that is to say, parallel to the plane of the web and sep-
100 arated by concrete (Fig. 2). Transverse bolts *b*, shown in their true form in Figs. 2 and 4, and represented symbolically by small black circles in Fig. 1, connect plates *p*, said bolts passing through the intervening concrete.

105 Figs. 5 and 6 show an alternative type of main tensile reinforcement more compact than the preceding one. It is made of two spaced built-up members separated by con- 110

crete and connected by transverse bolts b . Each member is composed of two plates p and three angles a riveted together.

- 5 The web members F and f (Fig. 1) consist of flat bars whose connections to the main tensile reinforcement have been obtained by using for two consecutive web members one single bar bent so as to form two parallel branches and an intermediate loop and placing the loop in the central interval between plates p . Part of the bolts b may conveniently be placed inside the loops of the web members. The web bars located near the center of the girder may be vertical. Each 10 of the others may have parts so inclined as to meet the bottom reinforcement at an angle α of 45° (Fig. 1). The vertical web members near the center and the inclined members near the supports may be straight from end 15 to end, while the remaining ones may be bent at some intermediate point so as to give their upper ends vertical directions. The web bars F cover the whole depth of the girder, but the bars f are shorter so as to save web metal. 20
- 25 Each of the two continuous built-up steel members used in the zone of greatest compression of the girder may comprise (Fig. 2) a vertical web plate p and four angles a riveted together. These members are embedded in 30 the concrete at a sufficient distance from each other to permit the upper ends of the web bars F to extend between them and are connected by transverse bolts b (Figs. 1 and 2) which pass through the intervening concrete. 35
- 35 Each of the web posts on the supports A and B (Figs. 1 and 3) may consist of two channels c connected by transverse bolts b and embedded in the concrete at a sufficient distance from each other to permit the ends of 40 the web bars nearest to the supports to extend into the intervening concrete filled space. The ends of the web posts may be connected to the top and bottom flange members by rivets or bolts. 45
- 45 In reference to the flange members, the web posts and the connection of the web bars to the tension flange members, just described, it must be stated that they represent particular arrangements designed for use in long 50 span bridges; but thin web structures based on the use of flat bars connected or held to a continuous main tensile reinforcement may be obtained with such reinforcements of any suitable type and any suitable coherent mass. 55
- 55 As a main tensile reinforcement, rods or bars of any appropriate section—steel shapes like angles, plates, channels, I-beams, etc.—laid, arranged, combined or connected in any suitable manner, will answer the purpose. To 60 improve the bond or friction between the main tensile reinforcement and the surrounding mass, bars or shapes provided with embossed surfaces in the manner of deformed bars or checkered plates are of assistance. Angles s (Figs. 5 and 6) or other suitable shapes con-

nected to the main tensile reinforcement act in similar manner. The use of shapes with embossed surfaces may be extended to the other metallic members including the web bars, if desired.

70

For the coherent mass, plain concrete is generally adequate even for thin webs, but when high compression stresses or other causes require a special strengthening of the concrete in the web, steel rods, shapes or members may be used for this purpose. For the regions of greatest compression the reinforcement, when necessary, may be obtained for instance by means of longitudinal bars or steel shapes, transverse ties, hoops, spirals, 75 transverse plates as described in Patent No. 910,837, or any appropriate combination of these types of reinforcement. Blocks of hard precast materials may also be employed in the manner shown in the above-mentioned patent. 80

75

Continuous structural steel shapes or built up members of comparatively large section and having a sufficient stiffness of their own, independent of the presence of the concrete, permit of a considerable augmentation of the resistance of compression flanges and in their mode of action are analogous to the steel cores in composite columns. Each of the two built-up members shown in Figs. 1 and 2 is a member of this latter kind. Greater stiffness, if necessary, could be obtained by interconnecting the members by means of horizontal lattice bars or short plates; it must be noted here, however, that for correct spacing of the compression flange bolts b (Fig. 1) these bolts 90 in connection with the intervening concrete filling between the built-up members act in the same manner as a lateral steel bracing. 95

90

Flat bars used as web reinforcements in the manner shown have valuable properties 100 which may be briefly set forth as follows: In a compound structure reinforced in tension by a main tensile reinforcement having web bars connected thereto, a favorable and comparatively simple distribution of the internal 105 compression stresses in the coherent mass is obtained by using closely spaced web bars of a width equal to the thickness of the web. In this ideal case, the stress distribution in all interior planes parallel to the faces of the web 110 is the same; on the other hand, the tension stress at any point may be considered as taken by the reinforcement and acting, therefore, in a known direction. Owing to these simplifications it is possible, through the study of the 115 mutual deformations of the steel and the coherent mass to determine the curves of maximum compression stresses in the coherent mass which give a clear picture of the internal stress distribution and enable 120 the computation of the stress at any point of the coherent mass or the reinforcement. Some of the compression curves for the girder shown in Fig. 1 have been indicated by dotted lines such as m o n under 125

115

120

125

130

- the assumption of a uniform loading over the entire span. The stress along each compression curve varies, but, for a given loading, the curves stand in a fixed relation to the 5 inclinations or curvatures of the web bars. When the web members are vertical, the compression curves, as a rule, are comparatively flatter and make with the main tensile reinforcement a smaller angle β than when the 10 web members are inclined. In the cases of vertical bars, the average stresses along the compression curves are comparatively high, while for inclined bars the average stresses are comparatively low. When the web members 15 are incurved so as to intersect the compression curves approximately at right angle, both the compression stresses and the elastic elongations of the web are reduced to minimum values. By proper inclinations or 20 curvatures of the web members it is thus possible to control within certain limits the values of the compression stresses in a web of predetermined thickness. The stress along each web bar is also variable and near the 25 main tensile reinforcement greater than in the vicinity of the compression edge of the girder. This explains why, as shown in Fig. 1, web metal may be saved by using a number of comparatively short bars f .
- 30 The web thickness may be determined from the actual web compression stresses taking into account, if necessary, the influence of the elastic elongations of the web upon the compressive resistance of the coherent mass. The 35 specific web elongations are maximum in the directions perpendicular to the compression curves; they may be lessened by increasing the amount of web metal so as to obtain low steel stresses or by giving the web members 40 directions more nearly perpendicular to the compression curves or both. Additional web members of suitable length, connected to the main tensile reinforcement may conveniently be used for this purpose.
- 45 The metallic web posts in the present structures are members whose function is to distribute into the web certain external or internal forces, thereby modifying the mode of action of these forces in a more favorable or suitable manner. The web posts on supports A 50 and B (Figs. 1 and 3) transmit the support reactions partly to the web members connected to them and partly to the coherent mass. The web posts thus prevent the concentration of 55 compression stresses which would otherwise occur in the lower part of the web at the supports if these posts were omitted without providing for adequate masses of concrete or coherent mass. An even distribution of the 60 support reactions on the whole depth of the girder is thus obtained with consequent reduction of the compression stresses in the coherent mass and increase of the ultimate shear resistance of the girder at the supports.
- 65 In connection with plain concrete as coherent

mass the present structures have over ordinary concrete constructions reinforced with square or round bars and stirrups two main advantages:

First: Whereas the distribution of the internal stresses in ordinary reinforced concrete girder structures is so complex that the latter can be proportioned only by approximate rules based largely on tests of actual girders, the present constructions can be proportioned accurately and without such tests from the actual internal stresses so that, besides obtaining, in all cases, structures of perfectly known resistance, it is possible to utilize the various materials to the extreme safe limit.

Second: For determined amounts of reinforcement in the tension flange and in the web, the present stress distribution given the least web compression stresses obtainable for a fixed web thickness and given inclinations or curvatures of the web members. The present constructions permit, therefore, a reduction of the web thickness, which is very important in the case of great spans.

In the practical arrangement of the web members careful consideration must be given to the spacing, the width and the end connections of these members in order to make them fully effective.

As the above simple and favorable web stress distribution is based upon the theoretical assumption that every point of the web is endowed with a certain resistance in tension furnished by the web reinforcement, this assumption should be warranted by adequately close spacing of the web members, bearing in mind that too widely spaced members will give rise to a different and less favorable stress distribution. As a rough and approximate indication, an average spacing of one-fifth to one-sixth of the depth of the girder between the points where the web bars meet the main tensile reinforcement is close enough to develop the full effectiveness of these bars. Such close spacing may of course, if desired, be restricted to certain parts of a girder or structure, thus confining the favorable stress distribution imparted by the flat bars to the regions of the structure where it appears of advantage. In regions of low shear the web reinforcement becomes comparatively unimportant and the spacing of the bars may, of course, be considerably greater than indicated above.

The described web stress distribution rests further on the assumption that the web bars are secured to the main tensile reinforcement. This condition may be fulfilled by any arrangement, device or contrivance capable of holding directly or indirectly the web bars firmly to the main tensile reinforcement. Direct connections by means of rivets, bolts, hooks or any suitable ties, may be used. Welding also is adequate. For indirect connections, plates, angles or other suitable

pieces may be interposed between the web bars and the main tensile reinforcement. In the case of main tensile reinforcements made partly or entirely of flat bars, the ends of these bars may be bent up into the web to form some of the web members.

Figs. 8 and 9 show an arrangement of this latter kind, some of the heavy flat bars p' composing the bottom reinforcement being bent up into the web and the remainder of the web bars riveted to the bottom reinforcement. It is also possible to build all web bars in one piece with the bars of the main tensile reinforcement; however, it is not intended to cover herein the arrangement in which all web bars are formed by simply bending and extending into the web the flat bars of the main tensile reinforcement as shown in Patent No. 893,640 (Fig. 2).

In the girder disclosed in Fig. 1 the web members are connected to the main tensile reinforcement indirectly by the coherent mass filling the central space between plates p (Fig. 4) and by the transverse bolts b placed inside the loops of the web bars. The web bars have a firm grip on the mass filling said space through the loops of the bars and the web stresses enter the main tensile reinforcement partly through the adherence or friction of the coherent mass on faces s' of plates p (Fig. 4) and partly through the bolts. When the loops extend sufficiently far into the main tensile reinforcement the web stresses may be transmitted to plates p without the help of the bolts. The connections of the web bars to the web posts or to the compression flange members must be governed by the stresses to be transmitted. In Fig. 1 the web bars F are simply extended between the webs of the upper built-up members and end post channels and terminate near the upper and end faces of the girder. In structures having no compression steel in the compression flange it is desirable to extend at least a sufficient number of web bars to points close to the compression face.

The internal distribution of the web stresses as set forth previously is, strictly speaking, only true for web bars covering the whole thickness of the web, that is to say, intercepting all web compression stresses. In practice, however, it is generally necessary to give the web a thickness somewhat in excess of the total width of the bars in order to protect the metal against corrosion. It is obvious that in order to obtain the greatest benefit from the flat web bars the latter should cover as much as possible of the thickness of the web. If the width of the web bars is gradually decreased in a web of fixed thickness, the uncovered part of the web thickness tends more and more to modify the web stress distribution; on the other hand, the bearing surfaces offered to the web compression

stresses against the web bars decrease and these stresses therefore increase. It is estimated, however, that structures in which the web bars cover not less than five-tenths of the web thickness may with sufficient accuracy be figured for the stress distribution corresponding to wide bars if proper allowance is made for the actual width of the bars. Such structures possess over ordinary reinforced concrete structures the advantages imparted by a more correct analysis of the internal stresses. The girder shown in Figs. 1, 2, 3 and 4 is provided with wide web bars each covering nearly the whole thickness of the web. This girder may be regarded as reinforced by a single set of web bars. Instead of one single set of wide bars it may be of advantage to use two or several sets of narrow bars, the combined width of the bars of the narrow sets being equal to the width of the bars which should be used in a single wide set.

The girder shown in cross-section in Fig. 11 has two sets of web bars F arranged oppositely, but the bars of one set may be offset, if desired, with respect to the bars of the other sets as shown in Figs. 5, 6 and 7 where two sets of narrow bars have been used in such a manner as to give a staggered arrangement of the bars. When two or several sets of narrow web bars are used, the spacing of the bars for each set should be as close as if one single set of wide bars were used.

On Figs. 10 to 17, inclusive, the various construction features described previously have been embodied in structures other than simple girders on two supports. Fig. 10 is a view in side elevation of one half of a cantilever system extending over five openings and resting on four pier supports. The structure is symmetrical about the vertical center line $m'm'$. Girder AD rests on two supports B' and E , and is provided with two cantilever arms AB' and ED , the first-named arm covering the entire end opening and the other arm a part of the center opening. Girder AD is made of two webbed parts Ag and hD and three struts gE , hE and iE meeting on support E . The webbed parts have main reinforcements both in the tension flanges and in the compression flanges with the exception of cantilever arm AB' in which the compression flange reinforcement has been omitted. Both tension flange and compression flange reinforcements are composed of two channels c and a central plate p (Fig. 11) arranged so as to provide two spaces for the accommodation of the web members F which consist here, as already mentioned, of two sets of narrow flat web bars placed opposite each other. The short independent girder in the central opening, of which only one half DM is shown, has a main tensile reinforcement consisting of two flat bars p and a compression flange reinforcement made of two channels c (Fig. 14).

Flat bars p and channels c are separated sufficiently to receive the web members F which comprise a single set of wide bars. In order to provide, for this independent girder, a hinged support at D (Fig. 10), two web posts may be utilized at this point, one of the posts forming the end of the girder and the other the end of the cantilever arm ED . To these posts may be secured steel brackets h, h' , separated by an expansion roller o , through the intermediary of which the girder end may be supported by the cantilever end.

Each of the web posts at B', g, i and D may consist of two channels and each of the struts gE and iE may comprise two channels c and a central plate p (Fig. 12). In strut hE the central plate is indicated as having been omitted (Fig. 13). Flange members, web posts and struts for this cantilever system, instead of being composed of comparatively light sections, as shown, may be made of heavy built-up members if necessary.

The web posts at B', g and i (Fig. 10) serve the same purpose as the end posts of the girder of Fig. 1 in preventing the concentration of compression stresses in the lower part of the web at these points, and the web posts at D distribute the steel bracket reactions uniformly into the web of the cantilever arm and the web of the short center girder.

The connections of the struts and web posts to the flange members may be effected by means of rivets or other appropriate fastening elements.

The struts (Figs. 12 and 13) may be encased in concrete, which material may also be used in the webs and flanges of the entire cantilever system.

All flange members, web posts and struts may be connected transversely by bolts, and the web-reinforcing members may have looped connections with the reinforcing members of the tension flanges.

In order not to complicate the drawing, the transverse bolts, loops of the web members and rivet connections at the ends of the flange members, web posts and struts have not been indicated in Fig. 10.

Fig. 15 is a view in side elevation of one half of an arch rib with the ends fixed in abutment walls. The structure is entirely symmetrical about the vertical axis m^2, m^2 . The arch rib has a main reinforcement in both the intrados flange HG and in the extrados flange $A'C$; the abutment wall has a main reinforcement near each end face GF' and CE' . Members B^2G and GD' are web posts whose purpose is to distribute gradually into the web the local compression stresses created at point G by the elbows in the flange members; their functions are, therefore, similar to those of the web posts previously described, and, like the latter, are most effective when they are connected to the web members. All flange members for

the rib and abutments as well as the web posts consist each of two channels c connected by transverse bolts b and separated sufficiently to accommodate the web members F (Figs. 16 and 17). As in the case of the previous cantilever system, heavy built-up members could be used instead of channels for the flange members and web posts of this arch structure if necessary. The web-reinforcing members may consist of one single set of bars F (Figs. 15, 16 and 17) having looped connections with the reinforcing members of the tension flanges. The material used in the webs and flanges may be concrete. Two channels arranged in the same manner as for the flange members have been provided at the bottom $F'E'$ of the abutment wall (Fig. 15). The transverse bolts, the loops of the web-reinforcing members and riveted connections at the points B^2, G, F', E', D' and C have not been shown on Fig. 15.

What is claimed is:

1. A reinforced concrete girder comprising a web portion extending throughout substantially its entire length and a flanged portion extending along its zone of greatest tensile stress, a tensile reinforcing member of greater width than the thickness of said web portion embedded in and extending along said flanged portion, and web reinforcing members spaced along said girder, from end to end each having a part anchored in said flanged portion and a part embedded in and extending across said web portion, said web reinforcing members comprising relatively thin bars of a width of not less than one-half the thickness of the web portion of the girder the greatest cross-sectional dimension of each bar being disposed in the direction of the width or thickness of the girder and, the distances between successive bars being not more than half the depth of the girder.

2. A reinforced concrete girder comprising a web portion extending throughout substantially its entire length and a flanged portion extending along its zone of greatest tensile stress, a tensile reinforcing member of greater width than the thickness of said web portion embedded in and extending along said flanged portion and sets of spaced web reinforcing members in side-by-side arrangement, each having a part anchored in said flanged portion and a part embedded in and extending across said web portion, said web reinforcing members comprising relatively thin bars, each having its greatest cross-sectional dimension disposed in the direction of the width or thickness of the girder, the combined width of the bars of the various sets being not less than one-half the width of the web portion of the girder and the distances between the successive bars of any set being not more than half the depth of the girder.

3. A reinforced concrete girder having

spaced main tensile reinforcing members embedded therein and extending in side-by-side relation along its zone of greatest tensile stress, and additional reinforcing members embedded in and spaced along said girder, each having a part extending between and anchored to said main tensile reinforcing members and a part extending crosswise of said girder from its zone of greatest tensile

10 stress towards its zone of greatest compressive stress, said crosswise disposed reinforcing members comprising relatively thin bars of a width of not less than one-half the thickness of the portion of the girder reinforced thereby, the greatest cross-sectional dimension of each bar being disposed in the direction of the width or thickness of the girder.

4. A reinforced concrete girder comprising a web portion extending substantially 20 throughout its entire length, a flanged portion along its zone of greatest tensile stress, a flanged portion along its zone of greatest compressive stress, a tensile reinforcing member of greater width than the thickness 25 of said web portion embedded in and extending along the flanged portion in the zone of greatest tensile stress, a compression reinforcing member embedded in and extending along the flanged portion in the zone of 30 greatest compressive stress, and web reinforcing members spaced along said girder, each having a part anchored to said tensile reinforcement and a part embedded in and extending across said web portion towards 35 said compression reinforcement, said web reinforcing members comprising relatively thin bars of a width of not less than one-half the thickness of the web portion of said girder, the greatest cross-sectional dimension of each 40 bar being disposed in the direction of the width or thickness of the girder.

5. A reinforced concrete girder having spaced main tensile reinforcing members embedded therein and extending in side-by-side 45 relation along its zone of greatest tensile stress, coupling elements spaced along said reinforcing members and connecting them through the intervening concrete, and additional reinforcing members embedded in and spaced along said girder, said additional reinforcing members having parts extending into the space between said main reinforcing members and looped about said coupling elements and parts extending crosswise of said 55 girder from its zone of greatest tensile stress towards its zone of greatest compressive stress.

6. A reinforced concrete girder having spaced main tensile reinforcing members embedded therein and extending in side-by-side relation along its zone of greatest tensile stress, coupling elements spaced along said reinforcing members and connecting them through the intervening concrete, and additional reinforcing members embedded in and

spaced along said girder, each of said additional reinforcing members having an intermediate portion extending into the space between said main reinforcing members and looped about a plurality of said coupling elements, and end portions extending crosswise of said girder from its zone of greatest tensile stress towards its zone of greatest compressive stress.

7. A reinforced concrete girder comprising a web portion and a flanged portion extending along its zone of greatest tensile stress, spaced main tensile reinforcing members embedded in and extending along said flanged portion, coupling elements spaced along said main tensile reinforcing members and connecting them through the intervening concrete, and web reinforcing members embedded in and spaced along said girder, said web reinforcing members having portions looped about said coupling elements and parts extending across said web portion.

8. A reinforced concrete girder comprising a web portion and a flanged portion extending along its zone of greatest tensile stress, spaced main tensile reinforcing members embedded in and extending along said flanged portion, coupling elements spaced along said main tensile reinforcing members and connecting them through the intervening concrete, and web reinforcing members embedded in and spaced along said girder, each of said web reinforcing members comprising a thin flat bar having its intermediate portion looped about a plurality of said coupling elements and its end portions extended across said web portion, the width of said bar being not less than one-half the thickness of said web portion and disposed crosswise thereof and the distances between the various bar end portions extending across said web portion being not greater than one-half the depth of the girder.

9. A reinforced concrete girder comprising a web portion and a flanged portion extending along its zone of greatest tensile stress, spaced main tensile reinforcing members embedded in and extending along said flanged portion, coupling elements spaced along said main tensile reinforcing members and connecting them through the intervening concrete, and sets of web reinforcing members embedded in and spaced along said girder in side-by-side arrangement, each of said web reinforcing members comprising a thin flat bar having its intermediate portion looped about a plurality of said coupling elements and its end portions extended across said web portion, the combined width of the bars of the various sets being not less than one-half the width of said web portion and disposed crosswise thereof and the distances between the various end portions of the bars of any set being not greater than one-half the depth of the girder.

10. A reinforced concrete girder comprising a web portion extending substantially throughout its entire length, a flanged portion along its zone of greatest tensile stress, 5 a flanged portion along its zone of greatest compressive stress, a tensile reinforcing member of greater width than the thickness of said web portion embedded in and extending along the flanged portion in the zone of 10 greatest tensile stress, a compression reinforcing member embedded in and extending along the flanged portion in the zone of greatest compressive stress, and web reinforcing members spaced along said girder, each having 15 a part anchored to said tensile reinforcement and a part embedded in and extending across said web portion towards said compression reinforcement, some of the parts of said web reinforcing members being extended continuously from said tensile reinforcement to said compression reinforcement and some being extended only part way across said web portion.
11. A concrete girder having spaced main 20 tensile reinforcing members embedded therein and extending in side-by-side relation along its zone of greatest tensile stress, coupling elements spaced along said reinforcing members and connecting them through the 25 intervening concrete, reinforcing members embedded in said girder and extending upwardly therethrough from its points of support, and reinforcing members, embedded in said girder, having intermediate portions 30 looped about said coupling elements at points separated from said points of support and end portions extending obliquely across the adjacent parts of said girder and terminating adjacent said upwardly-extending reinforcing members at points separated from 35 said points of support.
12. A girder, as defined by claim 11, of which each of the obliquely-disposed reinforcing members comprises a thin flat bar 40 of a width not less than one-half the thickness of the enveloping part of the girder, said bar having its greatest cross-sectional dimension disposed in the direction of the width or thickness of the girder.
13. A concrete girder having spaced main 45 tensile reinforcing members embedded therein and extending in side-by-side relation along its zone of greatest tensile stress, coupling elements spaced along said reinforcing members and connecting them through the 50 intervening concrete, reinforcing members embedded in said girder and extending upwardly therethrough from its points of support, and a plurality of spaced reinforcing members embedded in said girder at varying distances from each of said points of support, each comprising a portion looped about one of said coupling elements and a portion extending obliquely across the ad- 55 jacent part of said girder and terminating 60 adjacent one of said upwardly-extending reinforcing members.
14. A girder, as defined by claim 13, of which the obliquely-disposed reinforcing members comprise thin flat bars, each of a 65 width not less than one-half the thickness of the enveloping part of the girder, the distances between said bars being not greater than one-half the depth of the girder, and the greatest cross-sectional dimension of 70 each being disposed in the direction of the width or thickness of the girder.
15. A reinforced concrete girder having spaced main tensile reinforcing members embedded therein and extending in side-by-side 75 relation along its zone of greatest tensile stress, spaced main compression reinforcing members embedded in and extending in side-by-side relation along its zone of greatest compression stress, and additional reinforcing members embedded in and spaced along said girder, each having a part extending across said girder and anchored at its respective ends between said main tensile reinforcing members and said main compression reinforcing members, said additional reinforcing members comprising thin bars of a width not less than one-half the thickness of the enveloping portion of the girder, the greatest cross-sectional dimension of each bar being disposed in the direction of the width or thickness of the girder and the distances between successive bars being not greater than one-half the depth of the girder.
16. A reinforced concrete girder having 80 spaced main tensile reinforcing members embedded therein and extending in side-by-side relation along its zone of greatest tensile stress, spaced reinforcing members embedded therein and extending upwardly 85 therethrough in side-by-side relation from its points of support, and additional reinforcing members embedded in said girder, each having a part extending obliquely across the part of said girder adjacent one 90 of its points of support and anchored at its respective ends between said main tensile reinforcing members and said upwardly extending reinforcing members at points separated from said points of support.
17. A girder, as defined by claim 16, of which the obliquely-disposed reinforcing members comprise thin flat bars of a width not less than one-half the thickness of the enveloping part of the girder, the distances between successive bars being not greater than one-half the depth of the girder, and the greatest cross-sectional dimension of each bar being disposed in the direction of the width or thickness of the girder.

LOUISE MOCCKETTI,
Administratrix of the Estate of Ernest
Moccetti, Deceased.
